ADJUSTING MECHANISM FOR RADIO APPARATUS AND THE LIKE

Filed March 23, 1927 2 Sheets-Sheet 2

UNITED STATES PATENT OFFICE.

ARTHUR DORSEY, OF NEW YORK, N. Y.

ADJUSTING MECHANISM FOR RADIO APPARATUS AND THE LIKE.

Application filed March 23, 1927. Serial No. 177,817.

In application Serial No. 39,796, filed June 26, 1925, owned by the present applicant there is shown and described an adjusting mechanism for radio apparatus and the like in which provision is made for differential movement between the driven member and the drive member and relatively movable indicia at all times indicate to the operator their relative movements whereby the 5 nicest degree of adjustment may be obtained. The present invention relates to the incorporation of such improvements in mechanism of a particular type wherein problems peculiar to the organization of parts and 10 their relationship arise. More particularly, the invention has to do with an assembly in which a window plate is provided to cover the operating mechanism and in which the indicia are mounted behind the window and 15 observable through the windows therein and in which illuminated means for the indicia are carried by the window plate but at the rear thereof. The improvements are more particularly concerned with a construction 20 in which the member to be adjusted is itself supported with the adjusting mechanism so that the entire assembly becomes a unitary whole in that all of the parts have a common support. In carrying out this object of the 25 invention it is proposed, further, to associate the window plate with other parts so that when it is mounted in place it serves the additional function of assisting in the support of all of the parts and their main- 30 tenance in desired relation to the panel.

More generally, the invention seeks to provide mechanism of the character described which shall be simple in construction, cheap to manufacture, easy of assembly and readily 40 accessible for purposes of inspection, repair or replacement of elements thereof.

Another object of the invention is to utilize some of the necessary mechanical elements as light reflectors to assist in the effective illumination of the indicia at all times.

In realizing some of the objects of the invention certain of the elements in the assembly embody per se novel features rendering them particularly useful for their intended functions. One such element consists of a threaded thimble constituting part of the bearing for the driving shaft and adjustable to engage the window plate to clamp it in place on the panel.

55 The improvements will appear in greater

detail in connection with the description of the preferred embodiment illustrated in the accompanying drawings, wherein:

Figure 1 is a view in front elevation showing a panel having openings therein to receive the improved window plate. 60

Figure 2 is a view in vertical section through the window plate and adjusting mechanism and taken on the plane indicated by the line 2-2 of Figure 1 and looking in 65 the direction of the arrows.

Figure 3 is a view in rear elevation of the assembly shown in Figure 2, the parts being broken away to show the differential drive.

Figure 4 is a view in front elevation of 70 the adjusting mechanism with the panel and window plate shown in Figure 1 removed.

As the description proceeds it will be evident that the improvements are equally applicable to a construction in which the window plate is set into the front of a panel and one in which the window plate and the adjusting mechanism are mounted wholly in front of the panel. In either event, however, it is contemplated that the adjusting mechanism and the indicia and the source of illumination therefor shall all be at the rear of the window plate. In the preferred embodiment illustrated there is shown a panel *a* which may be the front wall of a radio set 75 and this wall has cut therethrough two circular holes indicated in dotted lines at *a'*, *a''*, in Figure 1 which intersect as at *a³* leaving a continuous opening. These holes may be cut conveniently in the front wall of any 80 radio set by means of a circular cutter or reamer to permit the improved adjusting mechanism as a whole to be applied to such set. The window plate *b* which is of ornamental configuration may be of moulded 85 composition having extensions on its rear face adapted to seat snugly within the opening formed by the holes *a'*, *a''*, in the panel, as appears clearly from Figure 2. As viewed from the front there appears on the window plate a hand-knob *c* on the operating 90 shaft *c'*, this knob being mounted preferably near the lower end of the window plate. Near the center of the window plate is an opening *b²* through which may be introduced 95 a light *d* carried in a socket *d'* which extends through the opening and is mounted on an insulating base *d²* which may be grasped by the fingers to introduce the light and socket 100 through the opening or to remove it there- 105

110

from, the mechanical and electrical connections therefor forming no part of the present invention.

Immediately above and below the light *d* 5 are formed windows *b*³, *b*⁴, through which indicia *e* and *f* are visible, these indicia being illuminated when necessary by the light. The lower indicia *e* in the illustrated embodiment is in the form of a graduated dial 10 revolute with the drive shaft *c'* while the upper indicia *f* revolves with the member to be adjusted as will later appear, differential gearing between the driving and driven members insuring that a relatively great 15 movement of the drive shaft shall bring about only a predetermined fractional movement of the driven member thereby permitting a nice adjustment as contemplated by the said co-pending application Serial 20 No. 39,796 filed June 26, 1925. The indicia *e* and *f* and the light *d* are all mounted at the rear of the window plate *b* whether this plate extends through the panel *a* or is supported in front thereof. A transparent 25 mica or celluloid sheet *g* is preferably mounted so as to extend across both the window openings *b*³, *b*⁴.

The drive shaft *c'* is secured to the operating knob *c* most conveniently through an 30 inset bushing *c*² and a set screw *c*³ extending through the hub of the knob and the bushing to engage the shaft. The shaft itself may be journaled in a two-part bearing consisting of co-operating threaded thimble *h*, *h'*, the 35 portion *h* being headed to seat on the inner face of the panel *a* and the portion *h'* being flanged to bear against the front face of the window plate *b*. By having the two portions threaded it is evident that they may be adjusted 40 relatively to clamp the window plate firmly in place against the panel regardless of varying thicknesses of panel and lend themselves quite readily to dismounting when necessary. The shaft 45 extends through these thimbles and has secured to its inner end a suitable drive mechanism for operating the member to be driven. One such suitable mechanism is shown and described in co-pending application Serial No. 159,755 filed January 8, 1927, owned by the present applicant consisting briefly in a friction disk *c*⁴ adapted to bear on the face of a curved plate *i* which is secured to the driven member. The curved 55 plate *i* has rack teeth *i*' engaged by a pinion *c*⁵ on the end of the drive shaft *c'* whereby the predetermined angular relation between the driving and driven members is always positively maintained. On the end of the 60 drive shaft *c'* is also secured a hollow spider *k* of circular form to which is secured in turn the lower indicia *e*, movement of which may be observed through the window *b*⁴.

65 The member to be adjusted in the case of

radio apparatus may be the condenser shaft which is not illustrated but is adapted to enter the sleeve shown at *l* and to be connected to the driven portion of the mechanism by the set screw *m* as will appear 70 later.

The driven plate *i* is shown as secured to a transmission element formed as a circular concave plate *n* which is carried by a sleeve *o* concentric with the sleeve *l* and in juxtaposition thereto and receiving the set screw *m* whereby the sleeve *o* and sleeve *l* may be coupled fixedly to the condenser shaft by the set screw *m* as heretofore pointed out. The circular concave plate *n* houses the adjusting mechanism heretofore described and is disposed immediately behind the light source *d* and its tapered wall is in such relation to the windows *b*³ and *b*⁴ and to the upper and lower indicia *e*, *f*, as to reflect 80 sufficient rays of light from the source *d* forwardly through the indicia to insure a high degree of visibility.

On the inner end of the sleeve *o* is mounted a frame *p* which performs several 90 functions. This frame has a downwardly extending arm *p*' in which the rear end of the drive shaft *c'* is journaled. It has two laterally extending arms *p*², *p*³, which are disposed within the circular rack *i*' and at 95 their ends are bent forwardly to support upwardly and downwardly extending plates *p*⁴, *p*⁵, these plates being conveniently attached as by rivets *p*⁶. The downwardly extending plate *p*⁴ which is generally semi-circular in outline is formed with an opening to receive one of the thimble portions *h*. The upwardly extending plate *p*⁵ extends under the inner periphery of the indicia *f* and serves to back it up as well as to assist 100 in the illumination by baffling the reflected rays to the best advantage. The sleeve *o* may have fastened thereon a retaining washer *o'* to hold the frame *p* in place while permitting free relative movement between the 105 frame and the revolute sleeve *o*. The construction described insures centering of the necessary fixed axes and rotation of the relatively revolute parts and gives stiffness and rigidity to the entire assembly and affords the bearing points which assist to carry 110 the weight of the operating mechanism. These bearing points when considered in conjunction with the bracket *q* now about to be described insure a firm mounting free 115 from vibration and displacement.

To support the adjusting mechanism and the condenser shaft (in cases where the condenser shaft is the member to be adjusted) a bracket *q* extends downwardly from the 125 top rear side of the window plate and to the rear of the adjusting mechanism and receives in its lower end the end of the sleeve *o* which is held against axial displacement with respect to the bracket by the 130

flange sleeve *l*. The condenser shaft and all of the adjusting mechanism described except the driving mechanism itself which as has been shown is carried directly in the 5 panel and in the window plate, are thereby supported from the bracket *q*. The means for securing the bracket will now be described. The window plate *b* has preferably moulded in it and extending rearwardly therefrom near its top end two threaded studs *b'*. The bracket *q* is formed in its upper end with a cross plate *q'* of greater width than the window plate and of greater width than the opening *a²* of the 10 panel in which the window plate is seated. Provision is made for the studs *b'* to extend through the cross plate *q'* when the parts are assembled and retaining nuts *q²* are applied to the studs so as to clamp the plate 15 against the rear wall of the panel and clamp the shouldered window plate firmly in place. It may be said, therefore, that this clamping arrangement at the upper end of the window plate and the clamp secured through the 20 threaded thimbles *h*, *h'*, afford a very simple and convenient means for mounting the window plate and utilizing it as one element of the retaining devices. The studs *b'* may 25 serve the additional function as binding 30 posts for wires *r* by which current may be led to the light *d*, but this forms no part of the present invention.

The unitary mounting described in connection with the supporting frame *p* with its 35 several arms is held against rotary movement and, in assembly, is properly centered to bring the scales *e*, *f*, in registry with their respective windows, by means of forwardly protruding lugs *p⁷* extending from the arms 40 *p⁶* which enter similar recesses moulded in the rear face of the window plate *b*. Since the reflector *n* carries the scales *e*, *f*, and is adapted to rotate it is necessary to hold the supporting frame *p* in fixed angular position 45 so that displacement of the entire unit will not result from such rotation.

The changes indicated hereinbefore either expressly or by implication and other changes involving only mechanical skill may 50 be made without departing from the invention so long as the general results emphasized are secured in apparatus of the character with which the improvements are to be associated.

55 What I claim is:

1. In adjusting mechanism of the character described, a window plate having openings therethrough to expose relatively movable indicia, driving and driven members carried with the window plate, the indicia being movable with such members, respectively, and means whereby movement of the driving members imparts predetermined movement to the driven member. 60

65 2. Adjusting mechanism of the character

described, including a window plate adapted to be mounted in an opening in a panel, driving and driven members carried with the window plate, operative connections between the driving and driven members carried therewith, a bracket to support the operating mechanism, and means engaging the window plate and the bracket to clamp the window plate in the panel. 70

3. In adjusting mechanism of the character described, in combination with a plate having a window therein, indicia mounted behind the plate, a drive shaft journaled in the plate and extending therethrough, a driven member in operative engagement with the driving member, a circular concave reflector carried with the driven member, means for supporting the indicia upon the reflector and behind the window in the plate, and a light source to illuminate the 75 reflector. 80

4. In adjusting mechanism of the character described, in combination with a window plate, driving and driven members carried therewith and operatively interconnected, relatively movable indicia carried by the plate and operated by the last named members, means to support said mechanism at the rear of the window plate and a frame mounted on the rear side of the plate to hold 90 the parts in predetermined fixed relation. 95

5. In adjusting mechanism of the character described, in combination with a window plate, driving and driven members carried therewith and operatively interconnected, means to support said mechanism at the rear of the window plate, a frame to hold the parts in predetermined fixed relation, and a bracket to support the frame and adjusting mechanism. 100

6. In adjusting mechanism of the character described, in combination with a window plate, driving and driven members carried therewith and operatively interconnected, means to support said mechanism at the rear of the window plate, a frame to hold the parts in predetermined fixed relation, a bracket to support the frame and adjusting mechanism, and means carried with the bracket to support the member to be adjusted. 105 110 115

7. In adjusting mechanism for radio apparatus, in combination with a panel on which the apparatus is supported, a plate connected with the apparatus and disposed on one side of the panel, a second plate disposed on the other side of the panel, and means for securing the two plates together with the panel therebetween whereby the adjusting mechanism is secured to the panel. 120 125

8. In adjusting mechanism of the character described, in combination with a window plate, driving and driven members carried therewith and operatively interconnected, means to support said mechanism at the 130

rear of the window plate, a frame to hold the parts in predetermined fixed relation, and means carried with the frame and engaging the window plate to hold the frame against 5 rotational movement.

9. In a radio tuning mechanism, a condenser shaft, a manually operable member, means to drive the shaft from the member, a window plate, a supporting panel, means 10 to mount the plate on the panel, means to mount the shaft and manual means upon the window plate, a plurality of indicia means, means to mount the indicia upon the window plate, and means to drive the indicia from 15 the manual means, the indicia being moveable at different rates of speed.

10. In adjusting mechanism of the character described, in combination, a window plate, means to mount the plate on a supporting panel, movable indicia mounted at 20 the rear of the plate and carried by the plate, means connecting the indicia whereby one moves at a predetermined different speed in relation to the other, means to connect the indicia to the device to be adjusted to effect 25 adjustment of the latter upon movement of the former, and light means mounted in the window plate at the rear thereof to illuminate the indicia.

This specification signed this 14th day of March A. D. 1927.

ARTHUR DORSEY.
